UNITED STATES PATENT OFFICE.

GEORGE JAMES GAWLEY, OF FLEET, ENGLAND.

PERCUSSIVE TOOL.

1,225,612.

Specification of Letters Patent.

Patented May 8, 1917.

Application filed April 24, 1916. Serial No. 93,291.

To all whom it may concern:

Be it known that I, GEORGE JAMES GAWLEY, a subject of the King of Great Britain, residing at Kent House, Fleet, Hampshire, 5 England, have invented new and useful Improvements in Percussive Tools, of which the following is a specification.

My invention relates to means whereby atmospheric pressure may be used as the 10 motive force in delivering percussive blows such as is necessary in using chisels, calking tools, percussive drills, hammers and the like.

The means which I employ for the purposes of my invention comprise a piston sliding in a cylinder or chamber, completely closed at one end in such a manner that admission of air, on one side of the piston, is impossible, whereby the relative movement 15 of the said piston and cylinder in one direction will tend to create a vacuum, while the return movement will be effected by the atmospheric pressure.

My invention will be readily understood 20 by reference to the accompanying drawings, in which:—

Figure 1 represents in sectional elevation the simplest application of my invention.

Fig. 2 is a longitudinal section illustrating 25 a modification of the invention.

Fig. 3 is a section on the line 3—3, Fig. 2, but drawn to a larger scale than the said figure, and

Fig. 4 is a view drawn to the same scale 30 as Fig. 2 but showing the parts in a different position.

In the arrangement shown in Fig. 1, *a* indicates the cylinder, which is completely closed at the end *b* and which for convenience I will refer to as the head of the cylinder, the said head being shaped so that it can be, for instance, placed in contact with the object to be driven, say, for instance, a nail or have formed in it a socket 40 as indicated by the dotted lines *b*¹ into which a chisel, calking tool, or other instrument can be introduced.

c is a piston sliding within the cylinder *a* and secured to a rod *d*, the end of which latter projects through the rear end of the cylinder and is provided with a knob or handle so that it can be readily grasped to withdraw the said piston and create a vacuum between the same and the head *b*.

50 It will be understood that when the piston *c* has been so drawn out and is released that

the air which enters behind the piston will act upon the latter and drive it forward so that it will impinge upon or against the head *b* with a momentum corresponding 60 with the weight of the piston and rod and the velocity.

In the apparatus illustrated in Figs. 2 to 4 the piston, instead of being pulled outward to produce the vacuum, is held stationary, the cylinder being moved relatively thereto. This apparatus comprises an outer cylinder *e* closed at one end by a disk *f* and having at the other end an anvil *g* upon which the blows of the tool are delivered, 70 the said anvil being, as shown, formed with a collar *h* between which and a collar *i* of the cylinder *e* a spring *j* is placed. Within the cylinder *e* is arranged the vacuum cylinder *k* the ends of which are closed by disks *l*, *l*¹ while within the said cylinder is arranged a vacuum piston *m*. The said vacuum cylinder *e* is connected by rods *n*, *n* with a handle *o* which in turn is fixed to a cylinder *p* which telescopes upon the cylinder *e*, 80 sufficient space being left between the said cylinders *p* and *e* to allow of the introduction of a spiral spring *q*. The vacuum piston *m* has attached to it a hammer face *r* and has also connected to it a rod *s* which 85 slides through the disk *l*¹ of the cylinder *k*; the outer end of the said rod *s* is notched at *t*, as shown in Fig. 3 and has arranged in conjunction with it spring pawls *u* designed to be separated by the wedge *v* upon the 90 handle *o* when the latter reaches the limit of its inward movement.

The operation of the apparatus is as follows:—

Assume the parts to be in the position 95 shown in Fig. 2, which is the normal position of the apparatus when not in use, the operator now takes the apparatus in his hands and pushes in the outer cylinder *p* against the pressure of the spring *q* with the 100 result that the inner cylinder *k*, which is connected with the cylinder *p* by the rods *n*, *n* is pushed inward so that its end *l* is moved away from the piston *m* to the position shown in Fig. 4, a vacuum being 105 thereby formed between them.

As the cap or handle *o* reaches the extremity of its inward movement, the wedge *v* comes into operative connection with the pawls *u* and separates them so that the head 110 of the piston rod *s* is disengaged from the said pawls with the result that, under the at-

- mospheric pressure which acts upon the piston *m* through passages in the disks *b*¹ and *f*, the said piston is propelled forward to strike the end *l* of the cylinder *k* which lies 5 against the anvil *g* and impart a blow upon the latter which blow is transmitted to a nail with which the anvil may be in contact, or to a tool which can be held in position in any suitable manner.
- 10 When the pressure upon the cylinder *p* is released the latter is returned from the position shown in Fig. 4 to that shown in Fig. 2 under the action of the spring *q* when the operation hereinbefore described can be 15 repeated.

The apparatus shown in Figs. 2 to 4 is primarily designed for driving nails, for which purpose the cylinder *e* has at the striking end a yielding spring foot *w* applied to it, the said foot being formed with a series of slots or openings to facilitate the adjustment of the tool. It will be understood, however, that a holder might be provided for a chisel or other tool.

25 Claims:

1. An apparatus for utilizing atmospheric pressure for delivering impacts comprising a chamber having a closed end adapted to be placed against the article to be struck, 30 the opposite end of said chamber being open to the atmosphere, a piston mounted in said chamber and adapted to be moved toward said closed end for delivering an impact thereto by atmospheric air entering said cylinder and means for moving said piston away from the closed end of the cylinder, whereby a vacuum will be created between the closed end of the cylinder and said piston.
- 35 2. An apparatus for utilizing atmospheric pressure for delivering impacts comprising a cylinder having an anvil at one end, a second cylinder slidably mounted in the first named cylinder, and provided with a closed end which is adapted to contact with said anvil, said second cylinder being 40 open to the atmosphere at its opposite end, a piston slidably mounted in the second cylinder and adapted to be moved away from the closed end to create a vacuum between 45 the piston and the closed end of the second cylinder, and means for moving the second

cylinder relatively to the piston whereby a vacuum will be created in the second cylinder on one side of the piston and atmospheric air will act on the opposite side of the piston. 55

3. Apparatus for utilizing atmospheric pressure for operating percussive tools, comprising a cylinder or chamber, closed at one end, an outer cylinder in which it slides, a piston sliding within the inner cylinder, a handle or extension connected to the said inner cylinder, a guard or shield on the said handle which telescopes over the outer cylinder, means for connecting the piston with the outer cylinder and a device in connection with the handle or extension for disconnecting the piston from the outer cylinder so that the said piston can move under 60 atmospheric pressure to strike the base of the inner cylinder, substantially as hereinbefore described. 70

4. An apparatus for utilizing atmospheric pressure for delivering an impact comprising a chamber having a closed end adapted to be placed in contact with the surface to be struck, the opposite end of the chamber being open to the atmosphere, a member slidably mounted in said chamber, and means for moving said member away from the closed end of said chamber to create a vacuum in said chamber between the closed end and member, said member being moved toward said closed end by atmospheric air 80 entering the open end of the chamber. 85

5. An apparatus for utilizing atmospheric pressure for delivering an impact, comprising a cylinder closed at one end, an outer cylinder in which the first cylinder slides, a piston slidably mounted in the inner cylinder, means for moving the inner cylinder relative to the piston for creating a vacuum between the piston and the closed end of the inner cylinder, means for detachably connecting the piston with the outer cylinder, and means for disconnecting the outer cylinder and piston so that the said piston can move under atmospheric pressure to strike the base of the inner cylinder. 90 95
